J. K. MICKLEY

MOTOR CONTROLLING APPARATUS

Filed March 26, 1927

UNITED STATES PATENT OFFICE.

JOSEPH K. MICKLEY, OF WESTERN SPRINGS, ILLINOIS, ASSIGNOR TO THE UNION SWITCH & SIGNAL COMPANY, OF SWISSVALE, PENNSYLVANIA, A CORPORATION OF PENNSYLVANIA.

MOTOR-CONTROLLING APPARATUS.

Application filed March 26, 1927. Serial No. 178,682.

My invention relates to motor controlling apparatus, and particularly to apparatus for controlling a motor from a remote point. Apparatus embodying my invention is particularly adapted for, though in no way limited to, use in railway braking systems comprising a braking bar located in the track-way and actuated by a motor controlled from a distant point.

10 I will describe two forms of motor controlling apparatus embodying my invention, and will then point out the novel features thereof in claims.

15 In the accompanying drawing, Fig. 1 is a view, partly diagrammatic, illustrating one form of railway braking system including motor controlling apparatus embodying my invention. Fig. 2 is a diagrammatic view showing a modification of the motor controlling apparatus illustrated in Fig. 1, and also embodying my invention.

Similar reference characters refer to similar parts in both views.

20 Referring first to Fig. 1, the reference characters 1 and 1^a designate the track rails of a stretch of railway track. Located on opposite sides of rail 1 and extending parallel therewith are two braking bars 2 and 3. Similar braking bars 2^a and 3^a extend parallel with rail 1^a on opposite sides thereof.

25 The braking bars 2, 3, 2^a and 3^a are operated by a motor, which as here shown is of the fluid pressure type and comprises a cylinder A containing a reciprocable piston 14 to which is attached a piston rod 13. The braking bars are operatively connected with the piston rod 13 through suitable linkwork including a bell crank 5 and a lever 4 pivoted at point 4^a. When piston 14 moves to the left each braking bar is moved toward the associated rail into its braking position in which it engages a side of a wheel of a railway vehicle traversing the rails 1 and 1^a. When the piston 14 moves to the right, however, into the position in which it is illustrated in the drawing, the braking bars are moved away from the associated rails out of engagement with the wheels of a passing vehicle and the bars then occupy their non-braking positions.

30 The supply of fluid pressure, usually compressed air, to the cylinder A is controlled by main air valves 27, 30, 33 and 35,

which main valves are in turn controlled by three electromagnetic pilot valves R, P 55 and N. Each of these pilot valves comprises a valve body 18 having a valve stem 19 therein controlled by a magnet designated by the reference character 17 with a suitable distinguishing exponent. The valve stem 19 is biased to its upper or normal position by a spring 20 and when in such position connects the associated pipe 22 with atmosphere through a port 21. When magnet 17 is energized the stem 19 moves downwardly against the bias exerted by spring 20, to its reverse position, and the associated pipe 22 is then disconnected from atmosphere and is connected with a source of fluid pressure, not shown in the drawing, 60 through pipe 38.

65 The main air valves are located in a valve body 39. This body contains a cylinder having a reciprocable piston 24 therein. The upper side of this piston is subjected to the pressure in pipe 22 from valve R. Carried by piston 24 is the main valve 27 biased to its upper or normal position by spring 28. When valve R is de-energized, piston 24 and valve 27 are in their upper 70 positions and port 37 is disconnected from port 25 and pipe 15 leading to the right-hand end of cylinder A. If, however, pilot valve R is energized, valve 27 is opened so that fluid pressure flows from pipe 38, 75 through port 37, valve 27, port 25 and pipe 15 to cylinder A, thereby driving piston 14 to the left and forcing the braking bars toward the rails.

80 Valve body 39 also contains a piston 29 which is controlled by valve P. Piston 29 in turn controls the main air valve 30 adapted to at times connect port 25 with atmosphere through port 31. When valve P is de-energized and valve 27 is closed, piston 29 and valve 30 moved into their lower positions as shown in the drawings under the influence of gravity. When valve 27 is open, however, fluid pressure in port 25 will raise valve 30, allowing this fluid pressure to exhaust to atmosphere through port 31 unless valve P is energized. When valve P is energized, the upper side of piston 29 is exposed to the pressure in the associated pipe 22. Since the area of piston 29 is greater than 100 that of valve 30 the valve 30 will be held in

its lower position even if valve 27 is open, and communication between ports 25 and 31 will thus be interrupted.

In similar manner valve N controls the pressure applied to the upper side of piston 32 reciprocable in valve body 39 and controlling the two main air valves 33 and 35. A spring 36 biases the piston and the valves controlled thereby to their upper positions 10 in which pipe 16 leading to the left-hand end of cylinder A is connected with atmosphere through port 40, valve 33 and port 34. When valve N is energized, pressure from pipe 22 forces piston 32 downwardly closing 15 valve 33 and opening valve 35, thus supplying fluid pressure to the left-hand end of cylinder A through port 37, valve 35, port 40 and pipe 16.

The pilot valves R, P and N are controlled in part by a series of pressure responsive devices D, E, F and G, each comprising a Bourdon tube 12 communicating with the right-hand end of cylinder A through a pipe 6. Each Bourdon tube 12 25 controls a contact 7 in such manner that all of the contacts 7 are normally closed, but that the contacts of the several devices D, E, F and G open successively as the pressure in the cylinder increases. For example, I 30 will assume that contact 7 of device G is open when the pressure in the right-hand end of the cylinder A is above 20 pounds per square inch and that the contacts of the remaining devices F, E and D are open 35 when this pressure exceeds 40, 60 and 80 pounds per square inch, respectively.

The magnet 17^R of pilot valve R may be controlled by contact 7 of any one of the devices, D, E, F or G, this selection being accomplished by means of a selector designated by the reference character H. The selector H may be located at a point remote from the braking apparatus, as in the control cabin of a classification yard car retarder system, and in the form here shown, comprises a manually operable lever 8 adapted to engage any one of several fixed contacts each designated by the reference character 10 with a suitable distinguishing exponent. Operatively connected with lever 8 is a second lever 9 adapted to engage any one of a plurality of fixed contacts 11 each provided with a distinguishing exponent. The connection between levers 8 and 9 is such that when contact 8-10^G is closed contact 9-11^G is also closed. Similarly, when any contact controlled by lever 8 is closed, the corresponding contact controlled by lever 9 is also closed. The selector H also comprises a segment 60 contact 11^P so disposed that when lever 9 engages any one of the contacts 11^G, 11^F, 11^E, or 11^D, the lever also engages the segment contact 11^P, but that lever 9 does not engage segment 11^P when contact 10^N is closed.

65 The selector H controls the supply of

energy to the magnets 17^R, 17^P and 17^N from a source of energy such as a battery 51 having an intermediate point thereon constantly connected with one terminal of each of the magnets through a conductor 54. One terminal of the battery 51 is connected with lever 8 and the other terminal of the battery 51 is connected with lever 9.

Pilot valve N is provided with a circuit which may be traced from the upper terminal of battery 51, through contact 8-10^N of selector H, wire 55, conductor 56, asymmetric unit 50, magnet 17^N and conductor 54, to battery 51. When this circuit is closed the polarity of the current supplied to the circuit is such that the current passes freely through the asymmetric unit 50 and magnet 17^N is therefore energized. When contact 9-11^P of selector H is closed, a circuit is closed for magnet 17^P which may be traced from the intermediate point of battery 51 through conductor 54, magnet 17^P, asymmetric unit 49, conductor 56, wire 57, contact 9-11^P of selector H, to the terminal of battery 51. Magnet 17^P is therefore energized. It will be seen that by virtue of this circuit current is supplied to the magnet 17^P over the same two conductors 56 and 54 as were used for supplying energy to magnet 17^N but the polarity of the current supplied to these conductors over the circuit just traced is opposite to the polarity of the current supplied to the conductors when contact 8-10^N is closed. It follows that the asymmetric unit 50 prevents the supply of current to magnet 17^N when contact 9-11^P is closed. In similar manner the asymmetric unit 49 prevents the supply of current to magnet 17^P when contact 8-10^N is closed.

The magnet 17^R is provided with a plurality of circuits each including an asymmetric unit and a contact 7 of one of the fluid pressure responsive devices D, E, F and G. For example, when contact 8-10^G of selector H is closed, current flows from the upper terminal of battery 51, through contact 8-10^G, wire 58, conductor 59, asymmetric unit 48, contact 7 of device G, wire 61, magnet 17^R and conductor 54 back to battery 51. Conductor 59 is also connected with wire 61 through an asymmetric unit 47 and contact 7 of device F, but the polarity of the current supplied over the circuit just traced when contact 8-10^G is closed is such that this current can flow through asymmetric unit 48 but cannot flow through asymmetric unit 47. It follows that when contact 8-10^G of selector H is closed, magnet 17^R is energized if and only if contact 7 of device G is also closed. If the pressure in the right-hand end of cylinder A rises above 20 pounds per square inch so that device G opens its associated contact 7, the magnet 17^R becomes de-energized, even though contact 7 of device F is closed, be- 130

cause current cannot flow through the branch including the latter contact and asymmetric unit 47. When contact 9-11^F is closed, however, the lower terminal of battery 51 is connected through wire 60 with conductor 59 and the polarity of the current supplied to magnet 17^R is then such that this current will flow through unit 47 and contact 7 of device F. It will be apparent that current 10 of the polarity then supplied to magnet 17^R cannot flow through asymmetric unit 48.

Conductor 63 is connected with wire 61 through two paths, one passing through asymmetric unit 46 and contact 7 of device 15 E, and the other passing asymmetric unit 45 and contact 7 of device D. When contact 8-10^E of selector H is closed the upper terminal of battery 51 is connected through wire 62 with conductor 63, and when contact 20 9-11^D is closed the lower terminal of battery 51 is connected with conductor 63 through wire 64. It follows that the asymmetric units 45 and 46 permit the control of magnet 17^R by device D or device E according as contact 25 9-11^D or contact 8-10^E of selector H is closed.

The asymmetric units 45, 46, 47, 48, 49 and 30 50 may be of any suitable type, such for example as the type disclosed and claimed in an application for Letters Patent of the United States, Serial No. 1,111, filed Jan. 7, 1925, by Lars O. Grondahl, for uni-directional current carrying devices.

In explaining the operation of the apparatus as a whole I will first assume that the parts occupy the positions in which they are shown in the drawing. Under these conditions all the contacts of the selector H are open so that all of the valves R, P and N are 35 de-energized; valves 27 and 35 are therefore closed, and valve 33 is open. Valve 30 is closed due to the weight of the piston 29. Piston 14 of motor A occupies its right-hand position and the braking bars are retracted. 40 The supply of pressure to both ends of motor A is interrupted and contacts 7 of devices D, E, F and G are all closed. If the operator wishes to move the braking bars to their braking positions he actuates selector H to 45 energize magnet 17^P and magnet 17^R. For example, if the operator wishes to apply pressure of 20 pounds per square inch to the cylinder A, he moves the selector H to the position in which contact 8-10^G is closed. 50 In this position of the selector contact 9-11^P is also closed. Magnet 17^P is therefore energized and magnet 17^R is energized over contact 7 of device G. Valve 30 is therefore held closed and valve 27 is opened 55 to admit pressure through pipe 15 to the right-hand end of cylinder A. The braking bars are therefore moved to their braking positions. When the pressure in cylinder A reaches 20 pounds per square inch, contact 7 of device G opens, interrupting the

circuit for magnet 17^R and allowing valve 27 to close. Magnet 17^P remains energized, however, and valve 30 remains closed so that the pressure is maintained in cylinder A. Should this pressure be reduced, as by leakage, to a value below 20 pounds per square inch, the consequent closing of contact 7 of device G would reopen valve 27 and permit pressure to be restored to 20 pounds per square inch. In similar fashion if the selector H is moved to a position in which the valve R is controlled over any of the other devices D, E or F, the pressure in cylinder A will be maintained at a value which will open the contact 7 of the device then controlling magnet 17^R. If the operator wishes to restore the apparatus to its normal condition he first moves the selector to the position in which contact 9-11^P is open thereby energizing magnets 17^P and 17^R and allowing the pressure in the right-hand end of cylinder A to exhaust to atmosphere through valve 30 and port 31. The operator then closes contact 8-10^N, thereby reversing valve N and supplying fluid pressure to the left-hand end of cylinder A. The piston 14 is therefore returned to its right-hand position, in which position it is shown in the drawing. If the operator then opens contact 8-10^N the consequent de-energization of magnet 17^N restores the apparatus to its normal condition by venting the left-hand end of cylinder A to atmosphere through valve 33 and port 34.

The four asymmetric units 45, 46, 47 and 48 may be replaced by only two asymmetric units as shown in Fig. 2. In this view the apparatus is the same as in Fig. 1 except that the wire 61 is connected with a wire 66 through an asymmetric unit 53 and with a wire 65 through an oppositely disposed asymmetric unit 52. Wire 66 is connected with conductor 63 through contact 7 of device E, and with conductor 59 through contact 7 of device G. In similar manner wire 65 is connected with conductor 63 through contact 7 of device D and with conductor 59 through contact 7 of device F. It will be plain that when contact 8-10^E of selector H is closed, current flows over contact 7 of device G, through asymmetric unit 53 to magnet 17^R. The asymmetric unit 52 prevents the flow of current under these conditions from conductor 59 through circuit 7 of device F to magnet 17^R. If contact 9-11^F of selector H is closed, current flows over contact 7 of device F and asymmetric unit 53 to magnet 17^R, and unit 52 then prevents the flow of current through contact 7 of device G. In similar manner the units 52 and 53 select 115 between contacts 7 of devices D and E depending upon the polarity of the current supplied to wire 63 and common wire 54. Thus when contact 8-10^E is closed, current flows over contact 7 of device E and unit 120 125 130

53 to magnet 17^R, and when contact 9-11^D is closed current flows to magnet 17^R over contact 7 of device D and unit 52.

The operation of the apparatus is the same as described in connection with Fig. 1 and will be readily understood without further explanation.

One advantage of apparatus constructed in accordance with my invention is that the entire control of the brake operating motor may be accomplished over four conductors, 56, 54, 63 and 59 extending between the selector H and the motor. Since the braking apparatus is sometimes located a considerable distance from the control cabin, the small number of line wires between these points is a feature which may result in considerable economy.

Although I have herein shown and described only two forms of motor controlling apparatus embodying my invention, it is understood that various changes and modifications may be made therein within the scope of the appended claims without departing from the spirit and scope of my invention.

Having thus described my invention, what I claim is:

1. In combination, a fluid pressure motor, 30 a magnet for controlling the admission of fluid to said motor, two devices responsive to the fluid pressure in said motor, a manually operable selector, and two circuits for said magnet both controlled by the selector and each controlled by one of said devices and each including an asymmetric unit.

2. In combination, a fluid pressure motor, 40 a source of current, a magnet for controlling the fluid pressure supplied to said motor and having one terminal connected with an intermediate point of the source, two contacts responsive to the fluid pressure in said motor, and manually operable means for at times connecting one terminal of the source with the 45 free terminal of the magnet through a first asymmetric unit and one said contact and for at other times connecting the other terminal of the source with such free terminal of the magnet through a second asymmetric unit 50 and the other said contact.

3. In combination, a fluid pressure motor, 55 a magnet for controlling the admission of fluid to said motor, two devices responsive to the fluid pressure in said motor, a manually operable selector, and means including asymmetric units for controlling the magnet by a selected one of such devices in accordance with the position of the selector.

4. In combination, a fluid pressure motor, 60 a magnet for controlling the admission of fluid to said motor, two devices responsive to the fluid pressure in said motor, a manually operable selector, two asymmetric units, a first circuit for said magnet controlled by one 65 said device and including a contact of the

selector and one of said asymmetric units, and a second circuit for said magnet controlled by the other said device and including another contact of the selector and remaining asymmetric unit.

70

5. In combination, a fluid pressure motor, a magnet for controlling the admission of fluid to said motor, a contact responsive to the fluid pressure in the motor, a source of current, means for reversibly connecting the 75 source with said magnet through said contact and a first asymmetric unit, and a branch around said contact and including a second asymmetric unit.

6. In combination, a fluid pressure motor, 80 a magnet for controlling the admission of fluid to said motor, two contacts responsive to the pressure in said motor, a pair of conductors, means for reversibly supplying current to the conductors, two asymmetric units, 85 means including one said unit for supplying current of one polarity from the conductors to the magnet through one of said contacts, and means including the other said unit for supplying current of the opposite polarity to 90 the magnet through the remaining contact.

7. In combination, a fluid pressure motor, 95 a magnet for controlling the admission of fluid to said motor, two contacts responsive to the fluid pressure in said motor, a source of energy having an intermediate point thereof connected with one terminal of the magnet, two asymmetric units, means including one such unit and one of said contacts for connecting the conductor with the free terminal of the magnet, means including the other said unit and the other said contact for connecting such free terminal of the magnet with the conductor, and manually operable means for connecting the conductor with one terminal or the other of the source.

100

8. In combination, a fluid pressure motor, 105 a pair of conductors, manually operable means for supplying the conductors with current of one polarity or the other, a magnet for controlling the admission of fluid pressure to the motor and having one terminal connected with one of said conductors, two contacts responsive to the fluid pressure in the motor, means for connecting the free terminal of the magnet with the other conductor through said two contacts in parallel, a first asymmetric unit inserted in series with one contact for permitting current of one polarity only to flow through the magnet and such one contact, and a second asymmetric unit inserted in series with the other contact for permitting current of the other polarity only to flow through the magnet and such other contact.

110

9. In combination, a fluid pressure motor, 115 a magnet for controlling the fluid pressure supplied to the motor, four contacts responsive to the fluid pressure in the motor, a first 120

125

130

conductor connected with one terminal of the magnet, a second and a third conductors, a first wire connected with the second and third conductors through a first and a second of the contacts respectively, a second wire connected with the second and third conductors through a third and a fourth of the contacts respectively, a first asymmetric unit connecting the first wire with the free terminal of the magnet, a second asymmetric unit connecting the second wire with such free terminal of the magnet, and a manually operable selector for reversibly connecting a source of current with the first and second conductors or with the first and third conductors, depending upon the condition of the selector.

10. Railway braking apparatus comprising a cylinder containing a reciprocable piston, a braking bar actuated by the piston, a first magnet for controlling the admission of fluid pressure to one end of the cylinder, a second magnet for controlling the exhaust of fluid pressure from such one end of the cylinder, a third magnet for controlling the admission and exhaust of pressure from the other end of the cylinder, a first conductor connected with one terminal of each said magnet, a second and a third conductor, a first asymmetric unit connecting the free terminal of said second magnet with the second conductor, a second asymmetric unit connecting the free terminal of the third magnet with the second conductor, two contacts responsive to the pressure in said one end of the cylinder, a third asymmetric unit connecting the free terminal of the first magnet with the third conductor through one of said contacts, a fourth asymmetric

unit connecting such free terminal of the first magnet with the third conductor through the other said contact, and a manually operable selector for reversibly connecting a source of current with the first and second conductors or with the first and third conductors according to the position of the selector.

11. In combination, a fluid pressure motor, a magnet for controlling said motor, two contacts responsive to the pressure in the motor and arranged to operate at different pressures, a circuit for the magnet having two branches including said two contacts respectively, means for supplying current of one polarity or the other to said circuit, and asymmetric units interposed in said branches for permitting current of one polarity to flow through the first branch but not the second and for permitting current of the other polarity to flow through the second branch but not the first.

12. In combination, a fluid pressure motor, a magnet for controlling said motor, two normally closed contacts responsive to the pressure in the motor and arranged to open successively as such pressure increases, a circuit for the magnet having two branches including said two contacts respectively, means for supplying current of one polarity or the other to said circuit, and two asymmetric units one included in each such branch for permitting current of one polarity to flow through the first branch but not the second while permitting current of the other polarity to flow through the second branch but not the first.

In testimony whereof I affix my signature.
JOSEPH K. MICKLEY.
